UNITED STATES PATENT OFFICE.

BERNARD GETLESON, OF SAN FRANCISCO, CALIFORNIA.

BOOT.

SPECIFICATION forming part of Letters Patent No. 289,525, dated December 4, 1883.

Application filed April 14, 1883. (No model.)

To all whom it may concern:

Be it known that I, B. GETLESON, of the city and county of San Francisco, State of California, have invented an Improved Boot; and I hereby declare the following to be a full, clear, and exact description thereof.

My invention relates to certain improvements in the construction of boots; and it is more especially adapted for heavy boots such as are used for farming and mining purposes.

In the accompanying drawings, Figure 1 is a view of my boot with attachment. Fig. 2 shows the device removed. Fig. 3 is a longitudinal section of a boot with the device attached showing the fastenings.

A is the leg, and B the foot, of a boot, which may be made in any desired or well-known form, this portion not being the subject of my present application for a patent.

It is often difficult to remove boots when they have become wet, and efforts to do so will break down the counter.

In order to render it easy to remove the

boot, I secure a plate, C, between the sole of the boot and the heel layers, allowing it to extend forward far enough to be held firmly in place. The rear end projects out slightly, and forms a catch, D, which may be hooked over any stationary object to assist in removing the boot, which may thus be easily done.

I am aware that it is old to secure a lug or plate in a recess cut in the bottom of the heel of the boot for the purpose of aiding in removal of such boot.

Having thus described my invention, what I claim as new, and desire to secure by Letters Patent, is—

In a boot, the plate C, secured between the heel and sole and projecting to the rear of the boot to form a catch for removing the boot, substantially as herein described.

In witness whereof I hereunto set my hand.

BERNARD GETLESON.
